UNITED STATES PATENT OFFICE.

HENRY T. WELCH, OF SAN JOSÉ, CALIFORNIA.

INHALER.

SPECIFICATION forming part of Letters Patent No. 406,118, dated July 2, 1889.

Application filed March 7, 1889. Serial No. 302,310. (No model.)

To all whom it may concern:

Be it known that I, HENRY T. WELCH, of the city of San José, in the county of Santa Clara and State of California, have invented 5 an Improvement in Inhalers; and I hereby declare the following to be a full, clear, and exact description thereof.

My invention relates to the class of medicinal appliances, and particularly to inhalers; 10 and my invention consists in the improved inhaler which I shall hereinafter fully describe and claim.

The object of my invention is to provide a 15 shapely and convenient appliance for covering the nose and causing medicinal fumes or vapor to constantly rise into the nostrils, whereby such affections as colds, influenza, and other forms of catarrh or derangement of the mucous membrane may be relieved or 20 cured.

Referring to the accompanying drawings, Figure 1 is a vertical section of my inhaler. Fig. 2 is a view showing the application of the 25 inhaler. Fig. 3 is a perspective view of the inhaler, showing the drawer B partially withdrawn.

A is a nose-covering, made of some flexible material stiff enough to retain its shape, and it may, if found necessary, be provided with 30 a small stiffening-plate a across the bridge of the nose. The base of the nose-covering is entirely closed in by a stiff plate a' , the back edge being curved to properly fit the upper lip. Upon this base-plate is formed a receptacle B, in which is placed the medicinal preparation, usually some absorbent material—such as felt—upon which a small quantity of the liquid is dropped. I prefer to make this 35 receptacle B in the shape of a drawer, which is adapted to slide to its seat between the base-plate a' and a top plate a^2 , the latter be-

ing perforated to permit the fumes to rise. The little drawer may be readily withdrawn to be resupplied, and as readily put back. In the front and sides of the nose-covering, just 45 above the top plate a^2 , are made a number of breathing-apertures C, here shown in the form of eyelets.

D are strings or tapes secured to the nose-covering and adapted to be tied behind the 50 head to hold the appliance in place.

The use of the inhaler is obvious. It is tied in place over the nose, and the fumes of the medicinal preparation rising enter the nostrils, and are inhaled with the air drawn 55 in through the breathing-apertures.

The appliance may be conveniently worn any length of time, and on account of its shape it is not in the way, nor is it very unsightly. It is not unduly aggravating, for the air is not 60 drawn through the medicinal preparation, but over it, whereby it becomes sufficiently impregnated.

Having thus described my invention, what I claim as new, and desire to secure by Letters 65 Patent, is—

An inhaler consisting of a covering or casing fitted to the nose, the movable drawer seated in the base of the covering or casing below the nostrils and containing the medicinal preparation, and the breathing-apertures in the front and sides of the covering or casing above the drawer, whereby the air drawn in through said apertures is impregnated with the rising fumes from the medicinal preparation, substantially as described. 75

In witness whereof I have hereunto set my hand.

H. T. WELCH.
